W. D. ALLEN.
CLASP FOR HOSE RACKS.
APPLICATION FILED MAR. 1, 1911.

1,059,100.

Patented Apr. 15, 1913.

UNITED STATES PATENT OFFICE.

WILLIAM D. ALLEN, OF CHICAGO, ILLINOIS, ASSIGNOR TO W. D. ALLEN MANUFACTURING COMPANY, OF CHICAGO, ILLINOIS, A CORPORATION.

CLASP FOR HOSE-RACKS.

1,059,100.

Specification of Letters Patent. Patented Apr. 15, 1913.

Application filed March 1, 1911. Serial No. 611,711.

To all whom it may concern:

Be it known that I, WILLIAM D. ALLEN, a citizen of the United States, and a resident of Chicago, county of Cook, and State 5 of Illinois, have invented certain new and useful Improvements in Clasps for Hose-Racks, of which I do declare the following to be a full, clear, and exact description, reference being had to the drawings forming part of this specification.

This invention relates more particularly to clasps designed for that class of hose racks in which the hose is suspended in pendent folds in such a manner that the hose 15 will occupy but little space when not in use, and can be quickly and easily withdrawn and brought into service.

Figure 1 is a view in side elevation of a hose rack embodying my invention. Fig. 2 20 is a vertical section on the line 2—2 of Fig. 1. Fig. 3 is a view of one of the hose engaging clasps in side elevation. Fig. 4 is a vertical section on line 4—4 of Fig. 3.

Referring to the accompanying drawings, 25 A designates the arm or bracket from which the hose B is suspended by the clasps G. The arm A is pivotally connected by the bolt D to the bracket E which is preferably made to be attached to the walls by screws. 30 The bolt D passes through the bracket arms E', E' and through the joint F to which the arm A is attached. This joint F is in no way a necessary feature as the arm A and joint F may be all in one piece. On the 35 arm A are hung a series of clasps G which are prevented from slipping off said arm A by a cap. A fold of the hose B is inserted between the jaws of each of the clasps G. One end of the hose may be run, as shown, to 40 a standpipe K, while the other may be equipped with a nozzle L.

It is in the clasps G that the chief feature 45 of the invention lies, though they may be varied in detail without departing from the scope of the invention. In Fig. 3 the side elevation of one of said clasps G is shown having an aperture g¹ through which the arm A is passed. The clasp G is made from two similar pieces, preferably of sheet metal 50 riveted securely together, as by rivets at g².

Below the lower rivets g² each of the two pieces of clasp G diverge and then converge, but do not come actually in contact again, thus forming the space g³ between the two parts above the lower half of the clasp. 55 The lower half of the clasp G is preferably widened so as to extend across a great part of the width of the hose that is to be inserted between the two jaws g⁴. The lower portions of said jaws g⁴ are preferably formed 60 with rounded corners g⁵ bent away from each other to facilitate the insertion of the hose between said jaws g⁴. Between the corners g⁵ on each of the jaws g⁴ a portion of the metal is by preference pressed in- 65 wardly to form a gripping portion g⁶ to hold the hose B more securely.

From this description it will be seen that when the parts are assembled, the hose is inserted in folds or festoons, each of the 70 clasps holding a single fold. Said folds are easily inserted between the jaws which are made sufficiently elastic to allow said fold to pass between them. The admission of the folds is further facilitated by having the 75 corners of the clasps bent outward, so that a fold need merely be pressed between the corners and it will slip on through between the gripping portions of the jaws. In case of sudden need, however, by seizing the nozzle, the folds will slip from between said 80 jaws g⁴ and the hose will be readily freed. The space g³ has two purposes that renders it easier to spread the jaws g⁴ and further 85 makes a space for the ends of the festoons or folds of the hose to rest in, so as not to be pinched and so injured. The actual holding portions are the parts g⁶ which contact with the hose at short distances from the ends of the festoons, leaving said ends to curve in 90 the spaces g³ and not be bent at sharp angles.

Having thus described my invention, what I claim as new and desire to secure by Letters Patent, is:—

A sliding clasp for hose racks, consisting 95 of two sheet metal members each having a large aperture in its upper portion to receive a sustaining arm, said members being securely united together to hold the aper- 100

tures of the members coincident, and each of said members having its lower end provided with an inwardly projecting, transverse rib to bite upon the hose, and with an outwardly bowed portion at a distance above said ribs and between said ribs and said aperture, whereby a space is formed at a

distance away from the biting ribs to receive a fold of the hose, substantially as described.

WILLIAM D. ALLEN.
